UNITED STATES PATENT OFFICE.

JOHN A. WHERRY, OF NEW ORLEANS, LOUISIANA, ASSIGNOR TO UNDERWOOD TYPE-WRITER COMPANY, OF NEW YORK, N. Y., A CORPORATION OF DELAWARE.

TYPEWRITING-MACHINE.

1,351,454.

Specification of Letters Patent. Patented Aug. 31, 1920.

Application filed December 1, 1917. Serial No. 204,968.

To all whom it may concern:

Be it known that I, JOHN A. WHERRY, a citizen of the United States, residing in New Orleans, in the parish of Orleans and State 5 of Louisiana, have invented certain new and useful Improvements in Typewriting-Machines, of which the following is a specification.

This invention relates to a collating device 10 for assisting in assembling, without the use of impaling studs, a plurality of work-sheets of different character in various predetermined relations to one another, so as to place them on the typewriter platen with certain 15 lines on the several sheets in register with one another.

In my application No. 184,820, filed August 7, 1917, (now Patent No. 1,300,905, dated April 15, 1919) a flexible collating 20 sheet or back extends around the platen and is provided with a series of impaling studs on each side, for maintaining a plurality of different perforated work-sheets in predetermined relative positions. The flexible 25 collating member positions the work-sheets in a pack on the platen. It is moved back and forth by spring-actuated lazy tongs, which maintain the flexible collating member taut on the platen.

30 In the present case, instead of using collating studs which require preparatory perforation of the work-sheets, clips are used, which do not necessitate previously perforated sheets, and preferably do not perforate 35 the sheets at the time of typewriting. The clips are located on a flexible collating back or member and pass around the platen with the same, and maintain the assembled pack of sheets in a smooth condition and preserve 40 their register.

The clips are maintained in their normal positions by spring means which yield slightly to allow for the bending of the work-sheets as they pass around the platen. 45 A certain amount of tension on the sheet is maintained. The clips are arranged in pairs tending to pull a sheet which they hold in opposite directions, so as to keep it smooth.

A suitable scale may be provided on the 50 flexible collating member to position the work-sheets relatively thereto and relatively to each other. This scale bears a definite relation to a pin effective to stop the backward rotation of the collating table

when the first line of writing is at the printing point. This pin may be adjusted on the collating member, so as to vary the amount of backward feed by securing it in any one of a plurality of holes.

55 Other features and advantages will hereinafter appear.

In the accompanying drawings,

Figure 1 is a perspective view, showing the collating device in its position ready to have the work-sheets assembled thereon before it is reversely moved to bring the assembled sheets to their starting position on the typewriter platen.

60 Fig. 2 is a spread perspective view of one of the clips, showing the different parts thereof before assembling:

65 Fig. 3 is a horizontal section, taken on the line 3—3 of Fig. 5, showing one of the clips in its active gripping position.

70 Fig. 4 is a view similar to Fig. 3, except that the clip is opened to either release a work-sheet or take in a work-sheet to be assembled.

75 Fig. 5 is a front view in elevation, partly broken away to show the underlying structure; the collating member being partly moved down in front of the platen.

80 Fig. 6 is a rear view of a portion of the flexible collating member, showing one of the clips and the spring for actuating the latter.

85 A platen 1 is mounted to rotate on a typewriter carriage 2. The platen and typewriter carriage are of the usual Underwood standard make. The platen 1 is rotated in 90 the usual manner either by hand knobs 3 or by line-space mechanism, indicated in general at 4.

95 For the purpose of holding the work-sheets on the platen, there are provided the usual pressure feed-rolls 5, which are mounted on rods 6 supported by bell cranks 7. The bell cranks 7 are arranged in pairs and are provided with arms 8, which engage flat sides 9 of a rock shaft 10, so as to be 100 operated by the latter. The rock shaft 10 may be operated from the usual pressure feed-roll release indicated at 11, which is connected to the rock shaft by a link 12 and an arm 13. The rock shaft 10 may also be 105 operated from a special release finger-piece indicated at 14, which is connected to the rock shaft 10 by means of a link 15, and a

line-space detent throw-off 16 connected to throw off the feed-roll 5 by means of a link 17 connected to an arm 17^a, extending from the rock shaft 10. When the platen is thus 5 released, a spring 18 (Fig. 5) becomes effective to withdraw a flexible collating member 19, preferably made of sheet-metal, so as to introduce work-sheets to bring the first line to the printing point. This mechanism is more fully described in my above-mentioned application.

For the purpose of assembling a plurality of work-sheets of different character, so that differently positioned lines on the work-sheets may be brought into register with one another, there is provided the collating back 19 which is in the form of a flexible member extending around the platen 1. To cause the collating member 19 to move evenly 15 with the platen, during its line-space or other movements, a connection in the form of sprocket teeth 20 is provided on the platen 1, to engage in openings 21 provided in the collating member 19. The flexible 20 collating member 19 is held smooth on the platen 1; the spring 18 and an opposing spring 18^a are each connected to lazy tongs 22 and 23, respectively, the latter being connected to the opposite edges of the collating 25 member 19. It will be understood that spring 18 is of greater strength than spring 18^a. Otherwise the collating member 19 would not be withdrawn automatically upon release of the platen from its detent. Both 30 the lazy tongs and the ends of the collating member may be guided by pin-and-slot connections to plates 24 and 25 provided on the typewriter carriage 2.

When the work-sheets are to be assembled or collated, the member 19 is adjusted to the position shown in Fig. 1, with the front end thereof extending considerably above the printing point of the platen 1, so as to bring a scale 19^a and clips 26, which 40 are used to position and hold the work-sheets, respectively, on the collating member 19, into view of the operator. To attach the work-sheets I employ the clips 26. There may be a series of these clips at one 45 side of the collating member 19, preferably at each side, all of them forming a plurality of sets which make it practicable to grip the work-sheets individually from opposite sides, or on only one side. The clips are 50 preferably arranged in pairs, the members of each pair being one above the other and acting in opposite directions, to maintain the particular work-sheet which they engage in a smooth condition upon the collating member 19, and also so as to maintain the work-sheets in proper position as they 55 pass around the platen 1.

Each clip 26 may include a frame 27, shown in the form of a plate having an 60 opening 28, Fig. 2. The plate 27 is pivot-

ally attached to the collating member 19 by means of a stud 29 which extends through an opening in the plate 27 and a hole in the member 19. The plate 27 forms one of the jaws of the clip, but is located on the under 70 side of the collating member 19. The other jaw of the clip, indicated at 30, is pivotally connected to the plate 27 and is on the upper side of the collating member 19, so as to rock toward and from the collating member 19 and plate 27. This pivotal connection is in the form of a hinge having one section 31 on the jaw 30, and two sections 32 on the plate 27. The sections 31 and 32 of the hinge are connected by a pin 33, 80 which permits the rocking of the jaw 30 toward and from the plate 27. The plate 27 is provided with a button 34, which extends through an opening 35 provided in the collating member 19, so as to directly engage 85 the work-sheet or sheets, and assist in making the clip 26 positive. This button 34 preferably does not pass through the work-sheet and is not, therefore, in the nature of an impaling stud.

The extent which the work-sheet can enter the clip 26 is limited by a gaging stud 36, which is secured to the plate 27, and extends through an opening 37 in the collating member 19 and through an opening 38 provided 95 in the upper clip jaw 30. The connection of the stud 36, with respect to the plate 27 and the upper jaw 30, is such as to allow a certain amount of relative movement, so as to enable the jaws to grip and release the work-sheets.

Normally, the jaw 30 is held with its gripping end against the button 34 of the plate 27 by means of a spring 39, which may be located at the opening 28 provided in the 105 frame or plate 27. The clip jaw 30 extends at its non-gripping end into the opening and is engaged by the spring 39. To release the clip and move the jaw 30 at its gripping end away from the plate 27, there is provided a 110 release device 41, shown in the form of a finger-piece or arm secured to the pivot 29. This finger-piece is provided with an engaging portion 42, which engages a cam 43 provided on the non-gripping end of the jaw 115 30 to press the latter end and raise the gripping end thereof. This causes the clip or clamp as a whole to spread (Fig. 4), and thus release the work-sheet held thereby or permit a work-sheet to be inserted therein.

The release 41 also acts to move the clip 26 as a unit about its pivot stud 29. This movement of the clip about the pivot stud 29 is permitted by making the openings 35 and 37 in the form of elongated slots. The movement of the finger-piece 41, about the pivot stud 29, is opposed by a spring 44 which is connected at one end to the collating member 19 (Fig. 6), and at the other end to an arm 45 secured to the pivot stud 120 125 130

29. This arm 45, when the release 41 is in its inactive position, bears against spring 39 on the side edge thereof and tends to swing the clip as a unit to a normal position determined by the limit of movement of the parts 34 and 36 in the slots 35 and 37. When the release is actuated, it rotates the pivot 29 and the arm 45 to swing away from the spring 39 and against the tension of the 5 spring 44, thus relieving the clip 26 of the tension of the spring 44. The portion 42 of the finger-piece 41 engages with the cam 43 on the non-clamping end of the jaw 30, but the tension of the spring 39 may be great 10 enough to prevent the actuation of the cam and the swinging of the jaw about its pivot at this time. Thus the clip, as a whole, will swing about its pivot 29 until the members 34 and 36 strike the opposite ends of their 15 respective slots, thus preventing a further movement of the plate 27; but the finger-piece 41 has an additional movement about its pivot to raise the clamping end of the jaw 30 by swinging the latter about its pivot 33 20 after the clip as a whole is arrested by the members 34 and 36 striking the ends of their respective slots. The cam 43 is then actuated by the finger-piece 41 against the tension of the spring 39 to open the clip for the 25 insertion of the paper. The finger-piece 41 is arrested in its extreme actuated position by a stop 46 secured to the plate 27. A work-sheet is now inserted between the clamping end of the jaw 30 and the button 30 34 on the plate 27, and the finger-piece is permitted to return to its normal position 35 under the tension of the spring 44. The first part of the return movement of the finger-piece is independent of the plate 27, to 40 clamp the work-sheet by setting the cam 43 free to be swung to its normal position by the spring 39. After the finger-piece 41 has moved clear of the cam 43, the arm 45 on the pivot stud 29 strikes against the spring 45 39, thus tending to swing the clip, as a whole, about its pivot 29 to its original or normal position. To insure the clamping of the work-sheet before the clip as a whole is permitted to return to its normal position, 50 there may be provided an extension or hook 43^a on the cam 43, which, when the clamp is in its effective or releasing position, engages in a hole 43^b in the collating member 19.

It will be remembered that the work-sheets 55 may be held by sets of clips, there being two in each set, which are so arranged that their springs 44 will tend to swing their clamping ends away from each other, thus keeping the work-sheets taut, Fig. 5. The release 41 for 60 the two clips of a pair move from opposite sides of their respective clips toward each other when brought into action. The springs 44 also act in opposite directions, so that the active ends of the clips of a pair are 65 yieldingly held by the springs 44 in the po-

sitions farthest away from each other. This is for the purpose of maintaining the work-sheets or sheets in smooth condition on the collating member, and to prevent any slackness of the work-sheets. The platen is 70 grooved or cut away at one or both ends at 49, to give clearance for the rows of clips.

The collating member 19, at the start, may be advanced to Fig. 1 position, with the front end thereof and the scale 19^a extended considerably above the line of writing at the printing point of the platen. The work-sheets, which may also have indices thereon, are then placed on the collating member 19, one by one, with the inter- 80 leaved carbon sheets, with the aid of the indices and the scale 19^a. Each work-sheet may be gripped individually to the collating member 19, to allow for different relative placements of the work-sheets. Preferably 85 a sheet is gripped by a pair of oppositely acting clips 26. Normally, the clips are in gripping condition. They are opened by the operation of the release 41. The action of this release is first to swing the clip as a 90 whole against the tension of the spring 44 about the pivot stud 29. A continued movement of the release 41 cams down the tail end of the jaw 30, so as to raise the active end thereof. For the case of the uppermost 95 clip 26 in Fig. 1, the movement of the active end of the clip will be downward, and for the clip next below the movement of the active end will be upward, so that the movement of these two clips, which form a vertically-spaced pair, will be toward each other at their active ends. The clips are held in this position until the work-sheet is inserted between the jaws of the clips; the sheet being positioned by its side edge engaging with the limiting studs 36. Then the pressure of the two releases 41 is removed, so as to permit first the spring 39 and then the spring 44 to act. The springs 39 cause the jaws 30 to come down in tight 100 engagement with the work-sheet, and at the same time the springs 44 tend to cause the active ends of the clips 26 to spread relatively to each other, so as to smooth out the work-sheet gripped by the pair of clips. If 105 desired, the work-sheet may be gripped on both side edges with the assistance of another pair of jaws provided at the right of the collating member 19. One or more other pairs of jaws located at lower levels 110 may be used similarly to grip other work-sheets and hold them taut on the collating member 19.

The collating member 19 may then be drawn backwardly and a reverse rotation 115 of the platen 1 effected to bring in superposed initial lines on the several sheets, which were brought into register with each other, into conjunction with the printing point of the platen. To permit this action, 120

the release 14 is actuated to throw off the feed rolls 5 and release the platen from its detent mechanism in a manner more fully described in my above-mentioned application.

The reverse rotation of the platen and the collating member 19 may be accomplished automatically, and the amount of reverse rotation determined automatically by means of the release 14 and the stop pin 19^b, which engages a bell crank 48, in a manner more fully described in my above-mentioned application. This arrangement, in addition to limiting the backward rotation of the platen 1 and the collating member 19, operates the release finger-piece 14, which may bring into play the pressure feed-rolls 5 which had been previously withdrawn to their active positions, so that they preferably assist in holding the work-sheets against the platen after a reverse insertion thereof. The typewriting may then go on, and the line-spacing mechanism be actuated to feed the work-sheet forward from line to line. As the flexible collating member is fed upwardly in front of the plate 25, the clips holding the work-sheet swing away from each other slightly to take up the slack caused by the bending of the work-sheet with the collating member around the platen.

It will be seen that when the work-sheets are held at one side edge thereof, the feed rollers 5 are effective to assist in guiding the loose end of the work-sheet around the platen. If, however, each side edge of the work-sheet is held by a set of clips, the feed rollers are not necessary to guide the work-sheet around the platen as it is held in a taut condition on the collating member, and may be fed to and from the printing point by the platen 1, which forms a driver for the collating member by engaging the latter by the teeth 20, as hereinbefore described.

Variations may be resorted to within the scope of the invention, and portions of the improvements may be used without others.

Having thus described my invention, I claim:

1. The combination with a platen having a curved surface, of a flexible collating member passing around said platen, and a plurality of securing devices for holding work-sheets on said collating member having a movement relative to said collating member and to each other, so as to allow for the bending and straightening action of said collating member and said work-sheets in passing to and from the platen and around the platen.

2. The combination with a platen having a curved surface, of a flexible collating member passing around said platen, and a plurality of securing devices for holding work-

sheets on said collating member having a movement relative to said collating member and to each other, so as to hold said work-sheets taut on said collating member.

3. The combination with a platen having a curved surface, of a flexible collating member passing around said platen, and a plurality of securing devices on said collating member for causing work-sheets to move with said collating member around the platen, said securing devices having spring means for taking up slack in said work-sheets between adjacent securing devices.

4. The combination with a platen having a curved surface, of a flexible collating member passing around said platen for carrying a plurality of work-sheets around said platen, spring clips for securing work-sheets to said collating member, and means for releasing said clips.

5. The combination with a platen, of a flexible collating member passing around said platen, a plurality of securing devices on said collating member, for holding a work-sheet thereon, and tensioning means acting on said securing devices for taking up slack in said work-sheet between said securing devices.

6. The combination with a platen, of a flexible collating member passing around the same, gripping devices for securing work-sheets to said collating member, and means for releasing said gripping devices.

7. The combination with a work-sheet-supporting member, of a plurality of clips for securing work-sheets on said member, said clips having spring means for allowing a limited relative movement between the different clips, so as to maintain work-sheets smooth on said supporting member.

8. The combination with a work-sheet-supporting member, of a plurality of clips for securing work-sheets on said member, said clips having spring means for controlling their gripping action, and spring means for controlling the movement of said clips individually relatively to said work-sheet-supporting member and to each other.

9. The combination with a work-sheet-supporting member, of a clip pivotally connected to said supporting member for securing work-sheets to said supporting member, the pivotal movement of said clip relative to said supporting member allowing for a relative movement between the work-sheet gripped by said clip and that portion of the supporting member adjacent to said clip.

10. The combination with a work-sheet-supporting member, of a clip adjustably mounted on said supporting member for securing work-sheets to said supporting member, said clip comprising a pair of gripping jaws, and a single means acting during one continued movement thereof to move said

1. The combination with a work-sheet supporting member, of a jaw adjustably connected to said supporting member, a second jaw adjustably secured to said first-mentioned jaw to coöperate therewith, so as to grip a work-sheet to said supporting member, and spring means connected both to said supporting member and said first-mentioned jaw, so as to yieldingly maintain both of said jaws in a normal position with respect to said supporting member. 65
2. The combination with a work-sheet supporting member, of a clip pivotally connected to said supporting member at one end, and slidingly connected to said supporting member at the other end, so as to adjustably secure work-sheets to said supporting member, said clip including spring means for yieldingly maintaining said clip in a normal position relatively to said supporting member. 70
3. The combination with a platen having a curved surface, of a flexible supporting member passing around said platen and arranged to carry work-sheets passing around said platen, and a pair of clips adjustably mounted on said supporting member for securing work-sheets to said supporting member, each of said clips including spring means for yieldingly holding said clips in a spread position with respect to each other, so as to allow said clips to have a relative movement toward and from each other, whereby the work-sheet gripped by said clips between said clips will be held taut on said supporting member and said platen. 75
4. The combination with a platen having a curved surface, of a flexible supporting member passing around said platen to travel with the rotation of said platen, clips having a movement relative to said supporting member as a unit, and having jaws having a movement toward and from the supporting member to grip work-sheets to said supporting member, and means on each clip for shifting said clips relatively to said supporting member, so as to adjust the position of said clip as a unit relatively to said supporting member, and also for shifting said jaws toward and from the plane of said supporting member, so as to control the gripping action of said clip. 80
5. The combination with a work-sheet supporting member having an opening therein, of a pair of pivotally connected jaws located on opposite sides of said supporting member and projecting to positions in contact with each other through said opening, and means for manipulating said jaws to grip a work-sheet, so as to secure it on said supporting member. 85
6. The combination with a work-sheet supporting member, of a jaw adjustably connected to said supporting member, a second jaw adjustably secured to said first-mentioned jaw to coöperate therewith, so as to grip a work-sheet to said supporting member, and spring means connected both to said supporting member and said first-mentioned jaw, so as to yieldingly maintain both of said jaws in a normal position with respect to said supporting member. 90
7. The combination with a work-sheet supporting member, of a jaw adjustably connected to said supporting member, a second jaw adjustably secured to said first-mentioned jaw to coöperate therewith, so as to grip a work-sheet to said supporting member, spring means connected both to said supporting member and said first-mentioned jaw, so as to yieldingly maintain both of said jaws in a normal position with respect to said supporting member, and means connected to said spring means to take up the tension thereof, and also coöoperating with one of said jaws to move one of them relatively to the other of them, and to adjust both of said jaws bodily relatively to said supporting member, whereby a gripping action of said jaws and the position of said jaws along said supporting member will be concomitantly controlled. 95
8. The combination with a work-sheet supporting member having an opening therein, of a clip jaw on one side of said supporting member having an opening in register with said first-mentioned opening, a spring extending in register with both of said openings, a clip jaw located on the other side of said supporting member and having a portion thereof in contact with said spring, and means for engaging one of said jaws to overcome the action of said spring, so as to determine the relative positions of said jaws and thus the activity of the clip comprising the jaws to secure a work-sheet on said supporting member. 100
9. The combination with a platen having a curved surface, of a collating device passing around said platen having a plurality of relatively yielding work-sheet securing points having a movement toward and from each other in the path of travel of said device, whereby said collating device will automatically give to take up a certain amount of slack caused by bending of work-sheets in passing around said platen and maintain said work-sheets taut on said collating device and around said platen. 105
10. The combination with a platen having a curved surface, of a flexible collating member passing around said platen, means for holding a work-sheet on said collating member, means for maintaining said collating member taut around said platen, and ten- 110
11. The combination with a work-sheet supporting member, of a clip pivotally connected to said supporting member at one end, and slidingly connected to said supporting member at the other end, so as to adjustably secure work-sheets to said supporting member, said clip including spring means for yieldingly maintaining said clip in a normal position relatively to said supporting member. 115
12. The combination with a platen having a curved surface, of a flexible supporting member passing around said platen and arranged to carry work-sheets passing around said platen, and a pair of clips adjustably mounted on said supporting member for securing work-sheets to said supporting member, each of said clips including spring means for yieldingly holding said clips in a spread position with respect to each other, so as to allow said clips to have a relative movement toward and from each other, whereby the work-sheet gripped by said clips between said clips will be held taut on said supporting member and said platen. 120
13. The combination with a platen having a curved surface, of a flexible supporting member passing around said platen to travel with the rotation of said platen, clips having a movement relative to said supporting member as a unit, and having jaws having a movement toward and from the supporting member to grip work-sheets to said supporting member, and means on each clip for shifting said clips relatively to said supporting member, so as to adjust the position of said clip as a unit relatively to said supporting member, and also for shifting said jaws toward and from the plane of said supporting member, so as to control the gripping action of said clip. 125

sioning means acting on said holding means for maintaining said work-sheet taut on said collating member.

21. The combination with a platen, of a flexible paper-carrier passing around said platen, means for holding a work-sheet on said paper-carrier, tensioning means to draw said work-sheet taut on said paper-carrier, and driving means for said paper-carrier.

10 22. The combination with a platen, of a flexible paper-carrier passing around said platen, means for holding work-sheets on said paper-carrier, tensioning means for maintaining said work-sheets taut on said 15 paper-carrier, and a scale on the latter by which the work-sheets may be positioned relatively thereto.

23. The combination with a platen, of a flexible collating member passing around 20 said platen, means for holding work-sheets on said collating member, a scale on said collating member by which the work-sheets may be positioned, means for feeding said work-sheets to the printing point, and an 25 element, which bears a definite relation to said scale, for stopping the feeding movement of the work-sheets when the latter reach the proper position at the printing point.

20 24. The combination with a platen, of a flexible collating member passing around said platen, means for holding work-sheets on said collating member, a scale on said collating member by which the work-sheets 35 may be positioned, spring means for feeding said flexible collating member to bring the work-sheets to the printing point, a release for said spring means, and an element, which bears a definite relation to the scale 40 on said collating element, to simultaneously render said release ineffective and stop the movement of said collating member when the work-sheets reach the proper position at the printing point.

45 25. The combination with a platen, of a flexible work-sheet or paper-carrier passing around said platen, studs on said paper-carrier for engagement with a side edge of a work-sheet to position the same sidewise 50 of said paper-carrier, a scale for positioning said work-sheet lengthwise of said paper-carrier, and means on said paper-carrier for holding said work-sheet thereon.

26. The combination with a work-sheet-carrier, of a pair of clips for holding a work-sheet on said carrier, each clip being pivotally mounted and comprising a pair of jaws and a finger-piece, spring means effective to hold the clamping ends of said

clips away from each other, said finger-pieces being movable toward each other, the first part of the movements of said finger-pieces being effective to swing said clips about their pivots, so as to bring the clamping ends thereof toward each other, means 65 for arresting the movement of said clips after they have been moved toward each other, and means effective by a continuous movement of said finger-pieces to separate the jaws of said clips.

27. The combination with a work-sheet-carrier, of spring means for holding a work-sheet on said carrier, and other spring means for holding said work-sheet taut.

28. The combination with a work-sheet-carrier, of a pair of clips for holding a work-sheet on said work-sheet-carrier, each clip comprising spring means for clamping the work-sheet, and other spring means for holding the work-sheet taut.

29. The combination with a work-sheet-supporting member, of work-sheet-holding devices movably mounted thereon, and tensioning devices tending to move said holding devices away from each other, and thereby hold in taut condition a work-sheet carried by said supporting member.

30. The combination with a work-sheet-supporting member, of means for holding a work-sheet in taut condition thereon, comprising a gripping device mounted for limited movement on said supporting member, means tending to maintain said gripping device in closed condition, means urging said gripping device to one of its limiting positions, means for moving said gripping device to its second limiting position, and there opening said gripping device, and means to prevent movement of said gripping device from said second limiting position, until said gripping device has been closed.

31. The combination with a work-sheet-supporting member, of a clip comprising a pair of gripping jaws movably mounted on said supporting member, for securing a work-sheet thereto, a device acting, during one continued movement thereof, to move said jaws relatively to each other, and to move said clip as a unit relatively to said supporting member, and means to prevent the return of said clip to its original position until said gripping jaws have been closed.

JOHN A. WHERRY.
